INVENTOR.

Frank E. Johnston.

BY

Thomas J. Donnelly
ATTORNEY.

UNITED STATES PATENT OFFICE.

FRANK E. JOHNSTON, OF DETROIT, MICHIGAN.

RADIATOR SHIELD.

Application filed January 24, 1927. Serial No. 163,161.

My invention relates to a new and useful improvement in a radiator shield adapted for use with a vehicle radiator and has as its object the provision of a shield which 5 may be mounted on the front of the radiator and particularly the lower portion thereof for preventing passage of air therethrough and preventing freezing of the radiator in cold weather, and permitting raising of the 10 temperature of the water to a degree of maximum efficiency of the engine.

Another object of the invention is the provision of a radiator shield of this class having a main body portion provided with 15 a reinforcement and carrying the layer of sound deadening material, so that the device, when mounted on the radiator, will not be productive of any undesirable noise.

Another object of the invention is the 20 provision in a radiator shield of this class of supporting hooks projected through passages in the radiator, so arranged that the device may be very easily and quickly mounted thereon, and the supporting hoop 25 so constructed that, when the shield itself is removed therefrom, the hooks may be left in position without marring the appearance of the vehicle radiator to any great extent.

Other objects will appear hereinafter.

The invention consists in the combination 30 and arrangement of parts hereinafter described and claimed.

The invention will be best understood by a reference to the accompanying drawings 35 which form a part of this specification and in which,

Fig. 1 is a front elevational view of the invention.

Fig. 2 is a fragmentary sectional view 40 taken on substantially line 2—2 of Fig. 1.

Fig. 3 is a perspective view of the hooks used in the invention.

The invention is adapted for use with a 45 radiator having a frame 7 and a radiator core 8, through which is formed the passages 9. In cold weather, the air circulating through these passages 9 for cooling the water, is often of such a temperature that it causes a cooling of the water or a lowering 50 of its temperature below that required for maximum efficiency of the engine, and particularly at the lower part of the radiator. In order to prevent this cooling of the water at the lower part of the radiator, 55 it is desirable to shut off the circulation of the cooling air from the passages at the

lower part thereof, and to accomplish this I have provided a shield comprising a main body 10 which may be made of metal or other suitable material, and having around 60 its edges at the inner side, a suitable reinforcing member 11 made from card board or other suitable material, over the edge of which the edge 12 of the main body 10 is bent. Secured to the reinforcing member 65 11 and the inner face of the main body 10 is a layer of sound deadening material 13 which may comprise felt or the like, and it will be noted, as shown in Fig. 2, that this layer of sound deadening material lies 70 between the radiator and the shield, and prevents contact of the doubled over edge 12 with the radiator, so that a noiseless shield is provided.

Formed in the sound deadening material 75 13 is an opening 14 which registers with an opening 15 formed in the main body, the edge 16 of the main body being doubled inwardly at this opening so as to retain the felt or other sound deadening material 13 in 80 position.

For supporting the device on the radiator, I have provided, as shown in Fig. 3, a supporting hook formed preferably from wire, and doubled upon itself to provide the retaining tongue 17, this retaining tongue being 85 formed by the formation of the two U shaped portions 18 and 19, projecting outwardly from which is an arm or prong 20 and 21 respectively, these arms or prongs 90 being projected through the passages 9 formed in the radiator, and having the ends 20' and 21' bent downwardly to prevent undue removal of the supporting hook therefrom.

It is evident that the tongue 17 will engage in the openings formed in the main body 10 and in the sound deadening material 13, this tongue 17 being of resilient material, so that it will spring out slightly as the shield is pressed downwardly thereon, thus 95 securely holding the shield in position.

It will be noted that the doubled over portion of the main body 10 engages the supporting member but the resiliency of the 100 tongue will hold these parts in close engagement so that rattling will be prevented.

In this way I have provided a radiator shield which is of simple structure and which may be very easily and quickly mounted 110 upon the radiator.

The supporting hook may be left mounted

in the radiator when it is desired to remove the shield, so that it may be easily and quickly placed thereon upon approach of cold weather.

5 By having the shield constructed in this manner, and mounted as described, a very simple and effective means is provided for preventing the freezing of the water in the radiator, permitting heating of the same to 10 the temperature of greatest efficiency of the engine.

While I have illustrated and described the preferred form of my invention, I do not wish to limit myself to the precise form of 15 structure shown, but desire to avail myself of such variations and modifications as may come within the scope of the appended claims.

Having thus described my invention what 20 I claim as new and desire to secure by Letters Patent is:

1. A radiator shield of the class described adapted for use with a vehicle radiator provided with horizontally extending openings 25 formed therein, comprising: a main body portion of comparatively stiff material; a reinforcing strip mounted on one side of said main body portion adjacent the edges thereof; a layer of yieldable material mounted on 30 the outer side of said reinforcing strip and on the inner surface of said main body portion, said main body portion and said layer of yieldable material having registering openings formed therein; a supporting hook 35 for engaging in each of said openings and supporting said shield; an arm projecting outwardly from said supporting hook and adapted for being inserted through said openings, and secured therein for retaining

said shield in operative relation to said radiator. 40

2. A radiator shield of the class described adapted for use with a vehicle radiator having a plurality of horizontally extending openings formed therein, comprising: a main body portion; a reinforcing member mounted on said main body portion around the edges thereof; a layer of sound deadening material mounted on said main body portion and adapted to engage said radiator, 50 said sound deadening material and said main body portion having registering openings formed therein; a supporting hook engaging in each of said openings; a plurality of arms projecting from said supporting hook, each 55 adapted for passage through one of the openings in said radiator and for being bent into angular relation thereto for preventing undue removal of the same therefrom.

3. A radiator shield of the class described 60 adapted for use with a vehicle radiator having a plurality of horizontally extending openings formed therein, comprising: a main body portion; a layer of sound deadening material mounted on said main body portion and adapted to engage said radiator, said sound deadening material and said main body portion having registering openings 65 formed therein; a supporting hook engaging in each of said openings; a plurality of arms 70 projecting from said supporting hook, each adapted for passage through one of the openings in said radiator and for being bent into angular relation thereto for preventing undue removal of the same therefrom. 75

In testimony whereof I have signed the foregoing specification.

FRANK E. JOHNSTON.
